UNITED STATES PATENT OFFICE

157,035

KEYHOLE ILLUMINATOR

Arnold I. Feuerman, Detroit, Mich.

Application July 26, 1947, Serial No. 140,549

Term of patent 14 years

(Cl. D48—20)

To all whom it may concern:

Be it known, that I, Arnold I. Feuerman, a citizen of the United States, residing at Detroit, in the county of Wayne and State of Michigan, have invented a new, original, and ornamental Design for a Keyhole Illuminator, of which the following is a specification, reference being had to the accompanying drawings, forming part thereof.

Figure 1 is a front elevational view of a keyhole illuminator, showing my new design.

Figure 2 is a top view thereof.

Figure 3 is an end view thereof.

I claim:

The ornamental design for a keyhole illuminator, substantially as shown.

ARNOLD I. FEUERMAN.
